C. SMITH.
INTENSIFIER.

APPLICATION FILED MAY 17, 1920.

1,397,788.

Patented Nov. 22, 1921.

INVENTOR

CHARLES SMITH,

by James L. Hopkins, ATTORNEY.

UNITED STATES PATENT OFFICE.

CHARLES SMITH, OF ST. LOUIS, MISSOURI, ASSIGNOR, BY MESNE ASSIGNMENTS, OF
ONE-HALF TO CLYDE M. METTLER, OF ST. LOUIS, MISSOURI.

INTENSIFIER.

1,397,788.

Specification of Letters Patent. Patented Nov. 22, 1921.

Application filed May 17, 1920. Serial No. 381,851.

To all whom it may concern:

Be it known that I, CHARLES SMITH, a citizen of the United States, residing at St. Louis and State of Missouri, have invented 5 certain new and useful Improvements in Intensifiers, of which the following is a specification, reference being had therein to the accompanying drawing.

My invention relates to improvements in 10 intensifiers and has for its object to provide a conducting element leading to the spark-plug, and composed of a mass of comminuted metallic particles which may be commingled with pulverized carbon and 15 glass, said mass being confined in a non-conducting receptacle and serving to convey the electric current.

The drawing is a longitudinal vertical 20 view in mid-section of a device embodying my invention.

I have illustrated the receptacle 1 as a 25 glass tube containing a mass 2 of comminuted materials which mass will be herein-after more particularly described.

The heads 3, of copper or like conducting 30 material form closures for the receptacle 1, and each head 3 has an integral projection 4 terminating in the eye 5.

Outside the heads 3 the tube 1 is filled 35 with a mass 6 of non-conducting plastic material which has integral lugs 8 extending into apertures in the tube 1 to hold said mass 6 against accidental displacement. The mass 2 comprises metallic filings preferably mixed with pulverized carbon and glass, and its particular metallic particles and carbon and glass content may be of various propor-

tions. In practice I have made up the mass 2 as follows; of brass or copper filings 70% by bulk; of steel or iron filings 25% by bulk; of nickel filings 2% by bulk; of silver filings, carbon particles and pulverized glass 1% of each by bulk.

The passage of the electric current through this mass has an intensifying effect like that 45 of the ordinary spark-jump, and the electric current still further comminutes and diffuses the carbon particles throughout the mass with the result of increasing the intensifying action.

Having thus described my invention, what I claim as new and desire to have secured to me by the grant of Letters Patent, is—

1. In an intensifier, a non-conducting receptacle having closures of conductive material; and a mass of comminuted conductive material held in place within said receptacle.

2. In an intensifier, a non-conducting receptacle having closures of conductive material; and a mass comminuted conductive material held in place within said receptacle, said mass comprising metal particles mingled with pulverized carbon and pulverized glass.

3. In an intensifier, a tubular container; heads of conducting material forming closures for said container, and having integral projections; and a mass of comminuted materials comprising metallic, carbon and glass particles held in place within said container and filling said container.

In testimony whereof I hereunto affix my signature.

CHARLES SMITH.
